UNITED STATES PATENT OFFICE.

LEWIS CLAYTON ERWIN, OF YORK, PENNSYLVANIA.

HARNESS.

SPECIFICATION forming part of Letters Patent No. 434,259, dated August 12, 1890.

Application filed May 29, 1890. Serial No. 353,587. (No model.)

To all whom it may concern:

Be it known that I, LEWIS CLAYTON ERWIN, a citizen of the United States, residing at York, in the county of York and State of Pennsylvania, have invented certain new and useful Improvements in Harness; and I do declare the following to be a full, clear, and exact description of the invention, such as will enable others skilled in the art to which it appertains to make and use the same, reference being had to the accompanying drawings, and to the letters and figures of reference marked thereon, which form a part of this specification, and in which—

15 Figure 1 represents a side elevation of my improved device applied to a portion of a vehicle-shaft; Fig. 2, a similar view of the same, looking from the inside; Fig. 3, a vertical transverse sectional view of the same; and 20 Fig. 4 a plan view of a pair of shafts or thills, showing the sleeves slidable and connected to the singletree.

The invention is designed as an improvement upon that class of detaching devices for 25 harness covered by my former patent, No. 369,282, granted August 30, 1887; and it has for its object to improve the efficiency of the same and obviate some of the defects found in practice to exist therein, as will be more fully 30 hereinafter described, and pointed out in the claims.

Referring to the annexed drawings by letter, *a* designates a portion of an ordinary vehicle-shaft, having affixed to it at a suitable point 35 a collar or sleeve *b*, which is provided on its inner side with a radially-projecting lug *b'*.

Embracing the collar *b* is a clasp consisting, essentially, of the two semicircular embracing portions *c c'*, hinged together under the shaft, 40 as at *c''*. The portion *c* is provided with an opening, into which projects the lug *b'* on the collar, and this part *c* has also formed on it an upward extension *d*, provided with a loop *d'* at its upper end for the attachment of the 45 back-band strap. The part *c* has also formed on or secured to it the lateral loops *f f'* for the attachment, respectively, of the hame and holdback straps. Formed on the upper end of the outer portion *c'* of the clasp is an upwardly-extending tongue *e*, which when the 50 clasp is closed upon the shaft fits in an opening in the bar *d*. A normally-depressed

spring-actuated bolt *g* is secured on the face of the bar *d* for the purpose of holding the tongue *e* in its recess and thereby keep the 55 clasp tightly clasped upon the collar *b*. The lower end of this bolt is beveled off in order that it will be raised automatically by the end of the tongue when the clasp is closed upon the shaft. To raise the bolt *g* and release the 60 tongue *e*, in order that the clasp may open and release the shaft, a cam-lever *h* is pivoted on the rear side of the bar *d* in the rear of the bolt. The lower or forward end of this cam-lever engages under a pin *g'*, secured to 65 the sliding bolt *g* and working in a slot *d'* in the bar *d*, and its upper or rear end is connected to an operating cord or wire *h'*, which may be carried through suitable eyes on the shaft back to within easy reach of the driver. 70 When the operating-cord is pulled on, the cam-lever raises the bolt *g* and releases the tongue *e*, whereupon the clasp falls open and releases the shaft. If desired, a spring *b''*, as 75 shown in dotted lines in Fig. 2, may be secured to the back of the clasp and adapted to bear upon the end of the lug *b'* to facilitate the disengagement of the clasp from the collar. It will be observed that one of these 80 devices is attached to each shaft of the vehicle, and the operating-cords may be attached together, so that both shafts may be released at the same time.

This invention provides simple means whereby all traces and singletrees may be 85 done away with, and whereby the horse may be quickly detached from the vehicle should he become unmanageable and dangerous.

Should it be desired, instead of affixing the collars *b* to the shafts they may be made slidable thereon and connected by tongues *k*' and rods *k* to the respective ends of the singletree, 90 as shown in Fig. 4. In my former patent the collar *b* was provided with annular flanges at each end, between which the parts of the clasp 95 fitted when closed; but this construction was discovered in practice to be defective, for the reason that the draft would cause the flanges on the collar to bind so tightly against the parts of the clasp that the outer part thereof 100 would not release itself readily when the locking-loop was raised. This difficulty is cured in the present invention by causing the rear part of the clasp, through the medium of the

lug b' , to receive all the draft, thereby leaving the outer portion c' free to fall outwardly when released.

The releasing devices in my former patent 5 were not positive enough, and the operating-cords, arranged as was necessary in said construction, were liable to become tangled and broken. These difficulties are obviated by the present invention, and a compact, durable, 10 and positive device produced.

Having thus fully described my invention, what I claim, and desire to secure, is—

1. The combination of a collar b , adapted to fit the shaft and provided with an inwardly-projecting lug b' , a clasp constructed of two hinged sections adapted to fit and clasp the said collar, the inner section of the clasp being provided with strap-loops and an aperture for the reception of the said lug b' , and means 20 for locking this clasp upon the collar, substantially as and for the purposes described.

2. The combination of the two-part clasp, the inner part being provided with an upright bar d , and the outer part with a tongue e , 25 adapted to fit within a recess in the bar d , a

sliding bolt provided with a pin and adapted to engage the said tongue e , a cam-lever carried by the bar d and adapted to engage the pin on the sliding bolt, and an operating-cord, substantially as described.

3. The combination of a collar adapted to fit the shaft, and provided with an inwardly-projecting lug b' , a clasp constructed of two hinged sections adapted to embrace the said collar, the inner section of the clasp being 35 provided with an aperture for the said lug, and an upright bar d , and the outer section with a tongue e , adapted to fit within a recess in the aforesaid bar d , a sliding bolt adapted to engage the said tongue e , a cam-lever carried by the bar d and adapted to engage a projection on the sliding bolt, and an operating-cord, substantially as described.

In testimony whereof I affix my signature in presence of two witnesses.

L. CLAYTON ERWIN.
